FLOYD B. CARTER, OF PLYMOUTH, OHIO, ASSIGNOR TO THE J. D. FATE COMPANY, OF PLYMOUTH, OHIO, A CORPORATION OF OHIO.

WARE-FORMING MACHINE.

1,202,028.

Specification of Letters Patent. Patented Oct. 24, 1916.

Application filed February 13, 1914. Serial No. 818,478.

To all whom it may concern:

Be it known that I, FLOYD B. CARTER, a citizen of the United States, and a resident of Plymouth, in the county of Richland 5 and State of Ohio, have invented a certain new and useful Ware-Forming Machine; and I do hereby declare the following to be a full, clear, and exact description of the invention, such as will enable others skilled 10 in the art to which it appertains to make and use the same, reference being had to the accompanying drawings, and to the characters of reference marked thereon, which form a part of this specification.

15 My invention relates to ware forming machines and it particularly relates to clay cutting machines.

20 My invention is particularly applicable to ware, formed by processes wherein the molded clay is linearly ejected from a forming die. The molded clay is then manipulated and cut up into parts as desired.

25 The invention particularly has to do with the cutting of the clay along a definite line without mutilation and withdrawing the cutter without injury to the ware, as well as with the manipulation of the clay preparatory to the cutting process.

30 In the constructions embodying my invention, the ware, such as tiles, bricks, and other clay products, preparatory to baking are cut by means of a stretched fine wire or similar cutter, while the formed clay is being conveyed through the cutting machine.

35 The invention may be contained in many constructions all of which come within the purview of my claims hereinafter appended. To show the practicability of constructions 40 embodying my invention, I have selected one of such constructions as an example and shall describe it hereinafter. The construction selected is illustrated in the accompanying drawings.

45 Figure 1 of the drawing, illustrates a side view of a machine embodying my invention, part of the frame work being removed in order to show more clearly the construction and operation of the machine. Fig. 2 is 50 a section of the cutting reel used for supporting the cutters. Fig. 3 illustrates in section, an indentation reel used in the manufacture, particularly, of bricks. Fig. 4 illustrates a section through the indentation arm. Fig. 5 illustrates a means whereby

the cutting arms or the denting arms may be removed from their supporting pins. Fig. 6 illustrates a side view of a part of the mechanism, showing a buffer for yieldingly holding the cutters. Fig. 7 is a transverse sectional view of part of the mechanism shown in Fig. 6.

Referring to the figures, 1 is a portion of the supporting frame. 2 are guide tracks for guiding the linked members 3 having the rollers 4 movable over the tracks 2. The linked members 3 are provided with supporting boards or conveyer plates 5. The plates 5 may be varied according to the shape of the molded clay, as, when bricks 60 are formed the plates may present flat upper surfaces, or if tiles are ejected from the molding die, the surface of the conveyer plates 5 may be cylindrical. The link parts 65 are each provided with end frames 6. The adjoining end frames 6 are kept in spaced relation. They are provided with cross pieces 7 located on the upper ends of the end frames 6 and form a spacing element 70 between the end frames. The cross pieces 75 are each provided with end frames 6. The adjoining end frames 6 are kept in spaced relation. They are provided with cross pieces 7 located on the upper ends of the end frames 6 and form a spacing element 80 between the end frames. The cross pieces 85 are each provided with end frames 6. The adjoining end frames 6 are kept in spaced relation. They are provided with cross pieces 90 between the end frames. The cross pieces 95 are each provided with end frames 6. The adjoining end frames 6 are kept in spaced relation. They are provided with cross pieces 100 between the end frames. The cross pieces 105 are each provided with end frames 6. The adjoining end frames 6 are kept in spaced relation. They are provided with cross pieces 110 between the end frames.

As the links 3 are shifted along by a suitable driving sprocket, the rollers 10 slip in between the end frames 6 and are propelled 105 by the movement of the links 3. They in turn cause reel 14 to be rotated so that the arms 11 are carried downward and into contact with the clay in succession. The distance between the edges 18 of the arms 11 is 110

the same as the length of the brick so that as the molded form passes beneath the reel, the upper surface is pressed inwardly by the edges 18 as the molded form passes along. 5 When bricks are to be formed, the alternate adjoining edges of the plates 5 are provided with upturned portions which press into the molded form 8 while it is received from the die. The upturned portions 20 are located 10 centrally with respect to the spaces, between the alternate end frames 6 so that the indentations formed by the arms 11 are located opposite the indentations formed by the raised portions 20. 15 The slots or notches 17 in which the arms 11 are located are made of a width sufficient to allow for any change of relation between the horizontally moving links 3 and end frames 6 and the rotary movement of the reel 14. The arms 11, as they are rotated, drop against one end of their associated notches 17 as they pass the vertical center line through the axis of the reel. In this position, they are carried down and enter 20 in between the frames 6 and the reel 14 is then propelled by contact of the edges of the frames 6 with the rollers 10. The reel plate 14 is keyed to the shaft 21 which has bearings in the standards 22 located at each 25 end of the shaft 21. 30 As the clay is carried along, whether in brick form or in tile form or in any other form that may be produced by ejection of clay through a die mold, it is cut by a suitable cutter. As illustrated in the drawing, the clay is cut by means of a wire cutter. Each wire cutter 30 is mounted on an arm 31 having a bifurcated end or cutter frame 32. The wire is secured at one end by means 35 of a suitable engaging hook 33. It is then passed over and through a channeled pin 34 of one furcation and to and through a similar channeled pin located on the opposite side of the frame 32 and to a threaded rod 36 and drawn tightly by means of a winged nut 37 located on the rod on the outside of the frame 32. The wire 30 is of suitable fineness so that when it is pressed against the clay it will cut it and sever it into portions. 40 The arm 31 is mounted in the wheel 40 and is pivotally connected therewith by means of a pivot pin 41 which is keyed to the wheel 40 by means of a screw bolt 42. The arms extend through slots or notches 43 45 and have free movements about the pin 41 but within the limitations of the slots 43. The arms are provided with steel catch pins 44 which penetrate recesses 45. The steel pins are spring pressed by means of the springs 46 which are compressed by means of the tap bolt 47. Each arm 31 is held 50 yieldingly in position with respect to the pin 41, by means of the spring pressed steel catch pin 44, which enters the recess or channel 45 formed in the pivot pin 41. The

pivot pin 41 is provided with a rounded or tapered nose, while the pin 44 is provided with a shoulder to prevent the spring 46 from pushing the pin 44 out of the counter-bored recess. Frequently while machines of 70 the type shown in the drawings are running, the wires break and ordinarily it is necessary to stop the machine in order to replace the broken wire. When the wire 30 breaks all that is necessary is to pull the cutter arm 75 off while the machine continues its operation and put another cutter arm in its place. This saves loss of a great deal of time in the operation of the machine. The inner end of the arm 31 is bifurcated and a roller 50 is 80 mounted between the furcations.

The reel 40 is mounted on the shaft 53 which has bearings in the standards 39. A cam 51 is connected to the supporting shaft 53 by means of a bolt 54.

As the links 3, together with the molded clay, are carried along, the rollers 48 secured to the pins 34 and 35, enter between the end frames 6 and are carried downward and vertically guided by the edges of the 90 end frames 6. As the rollers move down vertically with respect to the clay the wire 30 cuts the clay. The arms 31 when the rollers are moving vertically downward with respect to the horizontally moving clay, 95 propel the wheel 40 and bring the arms in succession downward and into cutting relation with the molded clay. The wires of the adjoining arms are spaced apart so that they will cut along the indentations formed 100 by the ridges 18 on the arms 11 and by the upturned portions 20 of the plates 5. Pins 49 located near the following side of the arms 31, make contact with the leading side of the end frames 6 as the cutters 30 are 105 withdrawn from the plate and so as to advance the cutter with respect to the clay as it rises from the bottom edge and passes the upper edge thereof. The cam 51, however, is so positioned on the shaft 53, such that 110 the rollers 50 press against the cam 51 and tilt the lower ends of the arms 31 forward so that it will follow the end surface of each preceding article as the links 3 pass the inclined portion 55 of the track 2. The 115 arms which at this point are rising upward while the movement of the end frames 6 which are at this point moving substantially horizontally with a slight declination. The pins 49 also operate to produce the clearance if the cam 51 becomes displaced or does not perform this clearing action correctly. The slots or notches 43 are long enough to allow the required change in relative movement between the rotated arms and the links 120 3. When the rollers 48 first pass between the end frames 6, the wheel 40, together with the arms, are propelled by the end frames 6 and the links 3. The arms 31, at this 125 time, press against the advanced ends of the 130

slots 43. As the frames are carried along during the process of cutting of the clay, they lag with respect to the movement of the wheel so that when the cutting portion, 5 performed by each arm, is complete, the arm is located in an intermediate position with respect to the ends of the slots 43. When the cutter 43 is to be withdrawn from the clay and advanced so that it will not engage 10 with the clay and to prevent mutilation of the clay, the rollers 50 on the arms 31 move against the cam 51 which lifts the outer end of the arm so as to clear the following piece of ware but not so as to strike the advance 15 piece of ware which at this point is passing down the declined portion of the track. When the cutter is clear of the clay, the cam 51 operates on the rollers 50 to raise the arms 31 against the leading ends of the 20 slots or notches 43. The arms are held against the advanced or leading ends of the slots or notches 43 by the cam 51 until the arms pass the vertical line through the axis of rotation whereupon they will be held 25 upon the leading ends of the slots or notches by gravity, and until they have completed the cutting operation of the clay each time they are brought in contact therewith for that purpose.

30 The cam 51 may be adjusted on the supporting shaft 53 and the bolts located in the collar 52 to which it is connected. Within the collar 52 is provided a brake 57 having preferably a leather face or strap 35 58 which is pressed against the hub 59 of the wheel 40 by means of the bolt 60 located in the collar 52. Any other suitable material may be substituted for the leather face or strap 58. This operates to retard the 40 movement of the wheel 40 which is actuated by the pressure of the end frames 6 against the rollers 48 on the ends of the arms 31. This prevents the wheel 40, together with the arms 31, from getting out of step with the end frames 6 and prevents any jarring 45 while the cutters are in the clay and prevents any engagement between the upper ends of the side frames and the rollers 48. The wheel 40 runs with a varying velocity 50 and the brake is to control the varying velocities of the wheel and keep the rollers 48 in contact with the end frames 6.

In order to prevent the effect of jarring 55 while cutters are passing downward through the clay, I have provided a means for keeping the rollers 48 in contact with the following end frame as the rollers pass down between adjoining end frames and to prevent any jarring or chattering of the roller 60 with respect to the end frame. By this means, the roller is pressed constantly against the leading edge of the following end frame, and a straight unmutilated cut is produced instead of a wavy or mutilated 65 cut. The pins 34 and 35 are extended

through the rollers 48 so as to form outwardly extending pins 60 which engage with the buffer lever 61. The lever has an arm 62 preferably curved upward so as to produce a substantially uniform resistance to 70 the pins 60 as they strike along the arms 62. The levers 61 are pivoted in brackets 63 which may be secured to the frame 1 by means of a screw bolt 64, at any suitable point along the frame in order to secure 75 the most efficient operation of the buffer lever 61 when used in connection with the rotating arms 31. The other end of the lever 61 is provided with a weight 65 which is cushioned by means of the rubber ring 80 66 located on a pin 67 secured on the bracket 63 when the weight drops downward as the lever 62 liberates the pin 60 located on the arm 31.

The buffer lever 61 engages the pins 60 85 of the arms 31 in succession so that as the arms are guided downward between the end frames 6 and the links 3 are propelling the wheel 40, the rollers 48 are pressed against the leading sides of the end frames 6 preventing 90 any effect of jarring to which the machine may be subject and also preventing mutilation of the cut.

The wheel 40, together with the hub 59 is rotatably mounted on the shaft 53 and is 95 held between the collar 52 and the ring 56 which is keyed to the shaft 53. The shaft 53 has bearings in the standards 68.

The construction selected and described may be greatly varied in the arrangement 100 and construction of its parts and in the substitution of the elements having equivalent functions and such modifications may still contain the invention.

What I claim as new and desire to secure 105 by Letters Patent, is as follows:

1. The combination of a clay conveyer having end frames, means for propelling the conveyer, a wheel, a plurality of radiating cutting arms having cutters and guide 110 rollers and pivotally mounted on the wheel, limiting stops located on the wheel and at the sides of the cutting arms to limit the movements of the arms relative to the wheel, the end frames for directing the guide rollers and cutters into cutting relation with the clay and for pressing against the rollers to propel the arms and the wheel, a cam, means for holding the cam in fixed relation with respect to the wheel, the inner ends of 120 the pivoted arms having rollers operated on by the cam to lift the cutters from the clay and the arms from the frames and to advance the arms with respect to the following frames and to bring and hold the arms to 125 and against the leading limiting stops while the arms are being raised by the wheel.

2. The combination of a clay conveyer, means for propelling the clay conveyer, a wheel, a plurality of radiating cutting arms 130

4. having cutters and pivotally supported on the wheel, end frames located on the clay conveyer engaging with the said arms to propel the arms and the wheel, limiting stops located on the wheel for limiting the movements of the arms relative to the wheel, a cam operating on the arms for periodically advancing each arm relative to the conveyer and the following end frame, a friction brake engaging the wheel for retarding the wheel and causing the arms to be pressed against the leading limiting stops of the arms.

3. The combination of a clay conveyer, means for propelling the clay conveyer, a wheel, a plurality of radiating cutting arms having cutters and pivotally supported on the wheel, end frames located on the clay conveyer engaging with the said arms to propel the arms and the wheel, limiting stops located on the wheel for limiting the movements of the arms relative to the wheel, a cam operating on the arms for periodically advancing each arm relative to the conveyer and the following end frame, a friction brake engaging the wheel for retarding the wheel and causing the arms to be pressed against the leading limiting stops of the arms, and a buffer means for successively engaging the arms to press them against the following frames.

4. The combination of a wheel, a plurality of cutting arms having cutters, the cutting arms pivotally connected to the wheel, a clay conveyer having end frames adapted to guide the cutters into cutting relation of the clay and propelling the cutter arms and the wheel and a weighted lever adapted to engage the ends of the arms as they are engaged by the end frames and keep the ends

of the cutter arms in constant contact with the side edges of the frames while the cutters are cutting the clay.

5. The combination of a wheel, a plurality of cutting arms pivotally connected to the wheel and having cutters, limiting stops located on the wheel at the sides of the arms, a clay conveyer having end frames for guiding the cutters into cutting relation of the wheel and propelling the wheel and the arms, a weighted lever for holding the cutters against the leading side edges of the end frames and means for retarding the wheel to prevent movement thereof, except as it is propelled by the end frames.

6. The combination of a rotatable wheel, a plurality of cutting arms pivotally connected to the wheel and having cutters, limiting stops located on the wheel at the sides of the arms, a clay conveyer having end frames for guiding the cutters into cutting relation of the wheel and propelling the wheel and the arms, a weighted lever for holding the ends of the cutter arms in succession against the leading side edges of the end frames while the cutters cut the clay to prevent vibration of the cutters, a cam for lifting the cutters clear of the clay during the withdrawal of the cutters from the clay and against the leading limiting stops and a friction brake for retarding the wheel to prevent movement of the wheel except, as it is propelled by the end frame.

In testimony whereof, I have hereunto signed my name to this specification in the presence of two subscribing witnesses.

FLOYD B. CARTER.
